UNITED STATES PATENT OFFICE

NATHAN WEIDNER, OF BRONX, NEW YORK

ATOMIZER

Application filed June 12, 1928. Serial No. 284,836.

This invention relates to improvements in atomizers and has particular reference to a perfume atomizer.

An object of the invention is to provide an improved atomizer of simple, practical and compact construction, which may be carried about the person or in a pocket-book, and from which the contents will not leak while the device is not in use.

10 The above and other objects will appear more clearly from the following detailed description, when taken in connection with the accompanying drawing, which illustrates a preferred embodiment of the inventive idea.

15 In the drawing—

Figure 1 is a side elevation of the atomizer constructed in accordance with the invention;

Figure 2 is a top plan view;

20 Figure 3 is a vertical longitudinal section on the line 3—3 of Figure 2; and

Figure 4 is an enlarged fragmentary sectional view through the atomizing chamber.

The atomizer of the present invention is particularly designed as a pocket device 25 which may be conveniently carried about by a person, and is shown in its preferred form as comprising a casing 5 of flat formation which is provided in its interior with liquid and air chambers 6 and 7 disposed at opposite ends of the casing. The bottom of the casing has mounted thereon a closure plug 8 for the chamber 6, which plug may be removed for the purpose of pouring into said chamber a supply of liquid, such as perfume.

35 Reciprocating within the chamber 7 is a plunger 9 provided with the rod 10 which extends through the externally screw threaded bushing 11 carried by the top of the casing. A nut 12 is secured to the outer end 40 of the plunger rod 10 for rotary movement relative thereto and when the device is in use said nut is threaded upon said bushing 11 to retain the plunger 9 in a depressed position against the tension of a spring 13 45 which is interposed between the lower end of the plunger and a plate 14 carried upon the inner end of a plug 16 screwed in the bottom of the casing. This plug is provided with an air passage 17 communicating with 50 the interior of the chamber 7 and normally

closed by a ball-valve 18. However, when the nut 12 is unscrewed from the bushing 11 the spring 13 forces the plunger 9 outwardly, thereby creating a suction which draws air into the chamber below said plunger. 55 Upon a depression of the rod 10 the valve 18 closes and the air in the chamber 7 is forced through the outlet pipe 19 and into the main pipe 20 joined to the pipe 19 through the coupling 21 carried by the lower end 60 of the chamber 6. Adjacent the upper end of the pipe 20 the same is provided with a branch 22 communicating with the interior of the chamber 6 above the level of the liquid therein. The air entering the chamber 6 65 through the branch 22 creates a pressure above the liquid which forces the same upwardly through a feed pipe 23, the upper end of which is supported in the head 24 and the lower end of which terminates short 70 of the filling plug 8. From the feed pipe 23 the liquid will enter the atomizing chamber 25 formed in the head 24 and will there be atomized in the manner to presently appear. 75

The upper end of the pipe 20 is connected through a coupling 26 mounted in the top of the casing to one end of an inner atomizing nozzle 27 projecting across the chamber 25 and into the screw threaded opening 28 of 80 said chamber. Said opening is closed by an outer nozzle 29 having a discharge duct 30 therein, said nozzle being adapted to be adjusted in the opening for a purpose which will presently appear. Carried in an inner 85 enlarged recess 31 of the nozzle 29 is a spring-pressed valve 32 which, when the nozzle 29 is screwed inwardly to its greatest extent will close the outlet of the nozzle 27 and at the same time close the inner end of the duct 90 30, thereby preventing leakage of the liquid from the atomizer when the same is not in use. When the nozzle 29 is adjusted to the position shown in Figure 4, the spring of the valve 32 moves the latter to an intermediate position. Thus when air pressure is created in the nozzle 27, said air passing from the pipe 20 and through the coupling 26, the liquid entering the chamber 25, also by reason of said pressure, will be atomized 95 100

at the outlet end of the nozzle 27 and forced past the valve 32 and through the duct 30, there being sufficient space between said valve and the wall of the recess 31 to permit of the 5 passage of said atomized liquid.

What is claimed is:

1. An atomizer including a casing, liquid and air chambers in said casing, means to establish communication between said chambers, means in said air chamber for transmitting air pressure therefrom to said liquid chamber to force the liquid therefrom, an atomizing chamber into which said liquid is discharged, an atomizing nozzle in the latter chamber communicating with said air chambers to receive part of the pressure therefrom to atomize the liquid in said atomizing chamber, a discharge nozzle through which the atomized liquid flows, and a sprung 10 valve carried by said discharge nozzle for closing the outlet end of said atomizing nozzle.
2. An atomizer including a casing, liquid and air chambers in said casing, means to establish communication between said chambers, means in said air chamber for transmitting air pressure therefrom to said liquid chamber to force the liquid therefrom, an atomizing chamber into which said liquid is 15 discharged, an atomizing nozzle in the latter chamber communicating with said air chamber to receive part of the pressure therefrom to atomize the liquid in said atomizing chamber, a discharge nozzle having a duct 20 therein and adjustably carried by said atomizing chamber for movement toward and away from said atomizing nozzle, and a valve supported in said discharge nozzle for closing said duct and atomizing nozzle when said discharge nozzle is moved toward said 25 atomizing nozzle.
3. An atomizer including a casing, liquid and air chambers in said casing, a main air supply pipe disposed between said chambers and communicating therewith, means in said air chamber for creating air pressure which is adapted to pass from said chamber into the liquid chamber through said air pipe, an atomizing chamber in communication with 30 said liquid chamber and also with said air pipe, an inner nozzle in said atomizing chamber for receiving air pressure from said air pipe, a feed pipe in said liquid chamber through which liquid is forced into the 35 atomizing chamber by the pressure entering said liquid chamber, a discharge nozzle having a duct therein and adjustably carried by said atomizing chamber for movement toward and away from said inner nozzle, and a 40 valve supported in said discharge nozzle for closing said duct and inner nozzle when said discharge nozzle is moved toward said inner nozzle.
4. An atomizer including a casing, an 45 atomizing chamber into which liquid is to

be discharged from said casing, an air nozzle in said chamber for atomizing the liquid therein, a discharge nozzle communicating with said chamber and through which the atomized liquid flows, and a valve carried 70 by said discharge nozzle and operable to close one end of said air nozzle.

In testimony whereof I have affixed my signature.
